United States Patent Office

Des. 209,260

Patented Nov. 14, 1967

209,260

COMBINED MIRROR AND STAND

Jack Kaye, 200 Kosciusko St., Brooklyn, N.Y. 11216

Filed Feb. 21, 1967, Ser. No. 5,904

Term of patent 7 years

(Cl. D86—10)

FIG. 1

FIG. 2

FIG. 3

FIG. 1 is a front perspective view of a combined mirror and stand showing my new design.

FIG. 2 is a top plan view.

FIG. 3 is a side elevational view.

The essential features of my design are shown in the full line disclosure.

I claim:

The ornamental design for a combined mirror and stand, as shown and described.
